CASING FOR X-RAY APPARATUS

Harry F. Waite, New York, N. Y.

Application July 31, 1935, Serial No. 33,942

8 Claims. (Cl. 250—34)

This invention relates to casings for X-ray apparatus and particularly to those which contain oil-immersed parts of the X-ray circuit, such as for example, the X-ray tube, transformers, etc.

5 The object of the invention is to provide a casing of this character containing X-ray apparatus particularly adapted for dental work, the casing being mounted in suitable supporting means to permit of its being pivotally moved to the various angles required to enable the apparatus to be properly used. The casing is so supported that all wiring leading into it is effectively protected and concealed and the use of wiping or other movable electrical contacts, generally used 10 where a relative movement is had between electrical parts and a support are wholly dispensed with. The casing is also so constructed that a liquid-tight container is provided and leakage of oil out of the casing is effectively prevented.

20 Reference is to be had to the accompanying drawing in which Fig. 1 is a vertical sectional view through the casing, a part of the supporting yoke therefor being shown partly in section; Fig. 2 is a sectional view through the casing, the view being taken at right angles to that of Fig. 1; Fig. 3 is an end view of the casing and supporting yoke therefor; and Fig. 4 is a sectional view on the line 4—4 of Fig. 1, looking in the direction of the arrows.

25 The casing is in the form of a shell, consisting of two parts, one of which is the part 5 referred to for convenience as the "body portion", and supported therewithin are the various parts of the X-ray circuit, including the X-ray tube 6, transformers 7 and filament transformer 8, these 30 electric elements being suitably connected by circuit wiring of conventional form which is omitted for simplicity in illustration.

35 Secured at the lower, or open end of the body portion 5 of the casing is a reinforcing bar 9 to which a ring 10 is attached by screws 11, said screws extending upwardly through the laterally extending peripheral flange 12 provided on the ring. A gasket or washer 13 is located between 40 the flange 12 and bar 9 to form a liquid-tight joint therebetween.

45 Secured to a laterally extending flange 14 at the lower end of the ring 10 is a closure plate 15. Screws 16 attach plate 15 to the flange 14 formed on the ring, and gasket 17 is interposed between flange 14 and plate 15 to produce a liquid-tight joint. With the arrangement described, it will be seen that the lower end of body portion 5 of the casing is closed by means of the ring 10 and its co-operating closure plate 15 so that the body portion 5 of the casing and co-operating parts 10 and 15 form a liquid-tight chamber which may contain oil in which the various parts of the X-ray apparatus are immersed. Plate 15 is provided 50 with a boss 18 threaded internally to receive lock-

ing ring 19 which holds the window 20 in place. The external threads on the boss 18 receive threaded bushing 50 and the threaded cone 20. Bushing 50 holds the lower or bottom member 21 of the casing in place.

5 By removing the cone 20 and bushing 50, the lower member 21 of the casing may be removed, and by removing screws 11, the ring 10 and the attached plate 15 may be easily removed, this action removing all of the circuit elements, including transformers 7 and 8 and the X-ray tube 6 also, which is secured to plate 15 by the clamps 22.

The transformers 7 and 8 are supported within body portion 5 by brackets 23 resting and secured upon the flange 12 on ring 10 by means of screws 24 (see Fig. 2). The upper end of these brackets are secured to the transformers by the bolts 25 and bolts 26 secure the filament transformer 8 to several of said brackets.

20 Extending from the opposite ends of the body portion 5 at diametrically opposite points are hollow trunnions 27 which fit within the bearings 28 and are capable of rotary or oscillatory movement therein. Bearings 28 are formed on 25 the ends of a casing-supporting bracket in the form of a yoke 29, which consists of two halves secured together at a central point by the bolts 30. The yoke is held in a suitable bracket 31 which is provided with holes 32 for reception of 30 screws or other fastening means intended to attach it to a suitable support. The two halves of the yoke 29 are hollow as shown in Figs. 1 and 2, and thus form conduits for wires 33 which lead into the bearings 28 and trunnions 27 mounted 35 therein, and are coiled or pig-tailed as shown at 34 in Fig. 1, with their ends attached to binding posts 35 located within the hollow trunnions 27 and extending through the walls of body portion 5. Binding posts 35 are insulated from the 40 walls of body portion 5, from the walls of trunnions 27 and from the bearings 28, as clearly seen in Figs. 1 and 4. The inner ends of the binding posts 35 are provided with heads 36 forming electrical contact surfaces against which 45 the free ends of leaf spring contacts 37 bear. The upper ends of the spring contacts 37 are secured by screws 39 to the insulated block 38 and wires leading from the screws 39 electrically connect contacts 37 to the transformer 7 and filament transformer 8. Each of the trunnions 27 is provided with a centrally located projecting stud 40 and a screw 41 extending into the end of said stud 40 attaches a cover plate 42 to the stud, said cover plate fitting into the end of the 55 bearing 28 and closing the same. The cover plate is calibrated as indicated in Fig. 3 and a fixed pointer 43 is provided on the adjacent arm of the yoke, as clearly shown in Fig. 3, to indicate the degree of inclination of the casing with re-

spect to the supporting yoke, when the casing is tilted during use of the apparatus.

It will be seen from the foregoing that all contacts, electrical wiring and parts of the apparatus are completely enclosed in a protective, liquid-tight, tiltable casing which holds the parts of the circuit immersed in oil. The manner of mounting the casing is such that it is freely pivotal in the supporting yoke 29. All electrical contacts are fixed, there being no wiping movement or any relative movement of parts of the circuit with respect to one another during pivotal or tilting movement of the casing relative to the supporting yoke 29. The pig-tailing of the wires 33 within the sockets 28 permits the pivotal movement of casing to any required extent without imparting strain on the wires or requiring sliding movement of contact members, and a compact, safe and thoroughly reliable structure results. Since the 10 transformers and tube are attached to the cover plate, composed of ring 10 and attached plate 15, these parts are removable with the cover plate as a unit and when replaced, springs 37, being brought into contact with members 36 at once 15 place the parts in circuit.

What I claim is:

1. In an apparatus of the character described, a casing having a body portion containing oil-immersed X-ray circuit elements, a supporting bracket in which said casing is pivotally mounted, said bracket being hollow and forming a conduit, hollow trunnions on the casing, bearings on the bracket in which said trunnions are pivotally mounted, electrical contacts located in the trunnions and extending into the casing and wiring extending through the bracket and entering the bearings and connected with the contacts located in the trunnions.

2. In an apparatus of the character described, a casing having a body portion containing oil-immersed X-ray circuit elements, a yoke in which the casing is pivotally mounted, said yoke having bearings at its ends, hollow trunnions at diametrically opposite points on the casing located within the bearings, electrical contacts located within the trunnions and insulated therefrom, said contacts having their inner ends disposed within the casing and connected to apparatus located therein, and wiring extending through the yoke and entering the bearings and extending into the trunnions and being connected to the electrical contacts located therein.

3. In an apparatus of the character described, a casing containing X-ray apparatus, said casing having hollow trunnions, electrical contact members located in the trunnions and projecting within the casing, a hollow yoke in which the trunnions are pivotally mounted, and electrical wiring extending through said yoke and entering the trunnions and connected to the contact members located therein.

4. In an apparatus of the character described, a casing containing oil-immersed X-ray apparatus, said casing having a body portion, a cover plate closing said body portion and forming a liquid-tight joint therewith, X-ray apparatus secured to said cover plate and removable out of casing as a unit with the cover plate when said cover plate is removed, trunnions projecting from the body portion, a supporting yoke in which said trunnions are pivotally mounted, electrical con-

tact members projecting from within the casing and extending into the trunnions, wiring extending through the yoke and connected to the contact members, and spring contact fingers carried by the X-ray apparatus for establishing electrical contact with the inner ends of the contact members within the casing.

5. In an apparatus of the character described, a casing containing oil-immersed X-ray apparatus, said casing having hollow trunnions, electrical contact members located in said trunnions and projecting into the casing, a hollow yoke having bearings at its ends in which the trunnions are pivotally mounted, electrical wiring extending through said yoke and bearings and entering the trunnions and connected to the contact members located therein, a cover plate on the casing, X-ray apparatus mounted on said plate, and spring fingers carried with said apparatus for establishing electrical contact with the parts of the contact members located within the casing.

6. In an apparatus of the character described, a casing containing X-ray apparatus, a hollow yoke in which the casing is pivoted, electrical contact members enclosed in the casing pivots, wires extending through the hollow yoke and connected to the contact members, a cover plate for the casing on which the X-ray apparatus is mounted, and spring contact members carried by the apparatus for establishing contact with the first-mentioned contact members inside of the casing when the cover is put in place on the casing and the apparatus carried thereby is moved into position within the casing.

7. An apparatus of the character described comprising, a hollow yoke-shaped bracket having bearings at its ends, a casing containing oil-immersed X-ray apparatus, said casing having trunnions pivotally mounted in said yoke, electrical contact members extending through the casing walls and projecting into the trunnions, means for removably closing the outer sides of the bearings and trunnions, wiring extending through the hollow yoke and entering into the bearings and trunnions, said wiring having slack portions located in the trunnions, the ends of said slack portions being connected to the contact members within the trunnions, a cover plate for the casing, X-ray apparatus carried by said plate and removable from the casing as a unit with said plate, and contact fingers carried with the apparatus for contacting with the parts of the contact members located within the casing when the cover plate and apparatus carried thereby are put in place on and within the casing respectively.

8. In an apparatus of the character described, a casing containing oil-immersed X-ray apparatus, a hollow two-part yoke in which the casing is pivoted, electrical contact members enclosed in the casing pivots, wires extending through the hollow yoke and connected to the contact members and having slack portions located within the pivots, a cover plate for the casing on which the X-ray apparatus is mounted, and spring contact members carried by the apparatus for establishing contact with the first mentioned contact members inside of the casing when the cover is placed on the casing and the apparatus carried thereby is placed in position within the casing.
